CLAIM

An ornamental design for a vehicle front fender, shown and described.

DESCRIPTION

FIG. 1 is a left side elevational view of a left vehicle front fender (the right vehicle front fender being a mirror image and is not shown);

FIG. 2 is right side elevational view of the vehicle front fender;

FIG. 3 is a front elevational view of the vehicle front fender;

FIG. 4 is a rear elevational view of the vehicle front fender;

FIG. 5 is a top plan view of the vehicle front fender;

FIG. 6 is a bottom plan view of the vehicle front fender; and,

FIG. 7 is a perspective view of the vehicle front fender.

Views are orthogonal projections rendered from computer aided design data.
